MEMORY PAD

Filed Nov. 14, 1927

FIG. 1.

FIG. 2.

UNITED STATES PATENT OFFICE

REBECCA E. HOOPER, OF HALF MOON BAY, CALIFORNIA

MEMORY PAD

Application filed November 14, 1927. Serial No. 233,230.

My invention relates to improvements in memory pads, and it consists in the combinations, constructions and arrangements hereinafter described and claimed.

5 An object of my invention is to provide a memory pad that has means for covering a portion of the work, causing the student to recall from memory the portions of the work thus covered and which has means for advancing the work covering shield so that an entire sheet of paper may be systematically gone over in order that by constant repetition the necessary problems will become memorized. The device may be used for all kinds 10 of problems, the learning of shorthand being one of the special uses to which the device may be put.

The invention employs several features which differ from other devices now on the 20 market. A guide for a ruler is so mounted that this guide may be moved vertically with respect to the pad. I term this member a floating guide. The second feature is the provision of a stop for the ruler that may be 25 swung into inoperative position when it is desired to remove the ruler from the topmost sheet of the pad in order that this sheet may be torn from the pad. A third feature resides in the posts which perform a double function. These posts clamp a pad of any thickness within predetermined lines to the support, and also act as uprights for the floating 30 guide.

Other objects and advantages will appear in 35 the following specification, and the novel features of my invention will be particularly pointed out in the appended claims.

40 My invention is illustrated in the accompanying drawing forming a part of this application, in which:

Figure 1 is a top plan view of the device;

Figure 2 is a section along the line 2—2 of Figure 1; and

45 Figure 3 is a section along the line 3—3 of Figure 1.

In carrying out my invention I provide a supporting back 1 that can be made of any desired material that is strong enough to withstand ordinary school use. To this support 50 I secure posts 2, the posts or uprights

being disposed at the right and left hand upper corners of the support. These posts have heads 3, see Figure 3, that prevent the posts from being withdrawn from the support 1. The posts are threaded for receiving knurled nuts 4. Sleeves 5 are also mounted upon the posts 2 and bear against a strip 6 that clamps a pad 7 to the support 1.

55 It will also be noted from Figure 3 that the posts not only pass through slots 8 in the support 1, but pass through openings 9 in a metal strip 10 that is disposed at the back of the support, as shown in Figure 2. A tightening of the nuts 4 will cause the sleeve 5 to clamp the strip 6 down against the 60 pad 7.

65 A ruler 11 extends at right angles from the strip 6 and is mounted upon a carriage 12 that has rollers 13 for slidably receiving a floating guide member 14. The ruler has perforations 70 15 for receiving the point of a pencil whereby a movement of the ruler will draw a line upon the pad 7. Additional perforations 16 may be disposed at spaced intervals, such as, for example: one inch apart. A scale is also 75 stamped upon the ruler and is indicated by the reference numeral 17.

The strip 6 also has a scale 18 thereon. Figure 3 shows how the member 14 is slidably 80 mounted upon the collars 5 so as to automatically adjust itself at the desired height above the pad 7.

85 The strip 10 carries a clip 19 for receiving a pencil 20. The bar 14 carries a grooved collar 21' that is slidably mounted on the sleeve 5. This collar rotatably receives a stop 21 that is adapted to enter a recess 22 in the carriage 12 when the stop is disposed in the position shown in Figures 1 and 3. This prevents the ruler from being moved off the pad. The stop may be swung about the collar 21'. 90 When the stop is swung to the left the carriage 12 may be moved so as to receive the post 2 in the slot 22. The carriage will carry the ruler 11 clear of the pad 7. This permits a sheet to be torn from the pad, if desired. The purpose of the stop is to keep the carriage from riding off from the pad. This makes it easy for the student to quickly move the ruler over the surface of the paper without 95 100

any chance of the ruler becoming engaged with the edge 24 of the pad.

A shield indicated by the dotted line 25 in Figure 1 is removably secured to the ruler 11 by clips 26.

From the foregoing description of the various parts of the device, the operation thereof may be readily understood.

A pad of any desired thickness may be secured to the support 1 by the strip 6 and the posts and nuts 2 and 4. If desired, the shield 25 may be dispensed with and the ruler 11 used for the drawing of a number of lines upon the uppermost sheet of the pad 7. The scales 17 and 18 permit these lines to be drawn in a predetermined manner. If it is desired to draw lines at an angle over the pad 7, the pad may be swung into the desired angle and then be clamped in place.

The device is especially adapted for memory work and when used in this connection the shield 25 is secured to the ruler 11 by the clips 26. At 27 I have shown shorthand characters and words representing these characters. The student would write the words "but", "can", and "it" after glancing at the shorthand characters in the row 28. The row 28 would then be covered by the ruler 11 and then the shorthand characters would be written in the row 29. Any number of rows may be provided in this way, and the ruler advanced to cover each row in order that the student may fix firmly in mind the various characters represented by the words.

I have already shown a problem at 30 which shows another use for the pad. The device may be used for purposes other than those shown, as for example: the device may be used as an ordinary composition tablet in which lines have been previously drawn on the paper by inserting the point of a pencil in any one of the desired openings 15 and moving the ruler 11 transversely across the pad.

Although I have shown and described one embodiment of my invention, it is understood that the same is susceptible of various changes and I reserve the right to employ such changes as may come within the scope of the appended claims.

I claim:

1. A device of the type described, comprising a support, uprights carried by said support, means carried by said uprights for clamping a pad to said support, a floating guide bar slidably carried by said uprights, a stop carried by one of said uprights, a ruler, means for slidably connecting said ruler to said guide bar, said stop normally preventing the movement of said ruler off from the pad, said stop being movable into inoperative position for permitting the ruler to move off from the pad.

2. In a device of the type described, a support, uprights carried by said support, means carried by said uprights for clamping a pad

in place on said support, a guide bar vertically movable on said uprights, a ruler, means for slidably connecting said ruler to said guide bar, and a single means carried by one of said uprights for securing the pad clamping means in place and for preventing the removal of the guide bar.

REBECCA E. HOOPER.
